UNITED STATES PATENT OFFICE

2,586,122

GYRATORY CRUSHER

Samuel William Traylor, Jr., Allentown, Pa.

Application February 6, 1948, Serial No. 6,633

12 Claims. (Cl. 241—209)

1

The present invention relates to crushers for material such as rock and ore. More particularly, the invention constitutes improvements in gyratory crushers in which crushing heads having mantles supported thereon are given gyratory motion with respect to downwardly facing concaves.

A primary object of the invention is to reduce the overall height of such crushers and to support the gyratory shaft from its lower end, instead of hanging the shaft in an upper bearing from above. In many crushers of the gyratory type, the gyratory shaft which carries the crushing head and mantel is suspended by bearings having spherical surfaces, in a spider carried by the upper frame section, and the lower end of the shaft is mounted, without bottom support, in the interior of a rotatable eccentric, by which gyratory movement is imparted to the shaft and head. Although such crushers have been found entirely satisfactory in use, numerous advantages flow in many cases from a construction in accordance with the present invention, in which the length of the shaft is reduced and the shaft is supported in a novel manner from below, within the eccentric.

A further object of the invention is to provide improved anti-friction bearing means for supporting a gyratory crusher shaft in the eccentric. Another object is to provide improved anti-friction bearing means for supporting the eccentric itself.

Another object is to provide improved structural features associated with the support or guiding means for the upper end of the gyratory shaft, to the end that this portion of the shaft may have universal movement about a central point of no motion.

Another object is to provide an improved connection between the upper frame section of the crusher and the bearing means for the upper end of the shaft, to the end that the upper frame may be adjusted vertically with respect to the lower frame and the crusher head, to adjust the space between the downwardly facing concave, carried by the upper frame section, and the upwardly facing crusher head, supported by the lower frame section.

A further object of the invention is to improve the lubricating system of a gyratory crusher. More specifically, the invention aims to provide an improved oil cooling system, including means for positively circulating the oil in heat exchange relation to cooling coils, through which a cooling medium is positively circulated.

2

Another object of the invention is to provide an improved and novel force feed oil circulating system, adapted positively to lubricate all bearing surfaces associated with the driving means, the eccentric, the bearing surfaces thereof and the thrust bearings for supporting the gyratory shaft and the eccentric.

Other and further objects and advantages will be apparent from a consideration of the following description of the illustrative embodiment of the invention shown in the accompanying drawings, in which,

Figure 1 is a vertical section and partial elevation of a crusher;

Figure 2 is an enlarged vertical section showing the supporting means for the lower end of the shaft;

Figure 3 is a horizontal section on line 3—3 of Figure 2, and

Figure 4 is a sectional detail taken on line 4—4 of Figure 3.

The crusher includes a fixed lower frame or casing 10, including a heavy cylindrical section 11 terminating at its lower end in an outwardly projecting, supporting flange 12. A plurality of inwardly extending webs 13 join a top housing section 14 having an upwardly projecting, centrally arranged hub 15. A lower or bottom housing section 16 may be bolted or otherwise secured to the housing 14, with an inwardly projecting annular plate or ring 17 interposed, for purposes hereinafter described.

The upper portion of the outer surface of the cylindrical section 11 of the fixed lower frame or casing 10 is shaped to provide a heavy screw thread 18, upon which a cylindrical member 19, constituting a part of the upper frame section 20, is supported for vertical adjustment by relative rotation with respect thereto, the member 19 having a complementary screw thread 21 formed on its inner circumference. A locking ring 22, disposed below the cylindrical member 19, serves to secure the parts in adjusted position. The upper frame section 19 is shaped to provide an upper, outwardly turned annular flange 23, upon which is mounted a ring 24, constituting a seat for a plurality of inwardly projecting arcuate members 25, each having an upwardly and inwardly inclined flange 26 upon which the backing 27 is mounted. The backing 27 and its supporting means may be constructed substantially as shown and described in my co-pending application Serial No. 743,078, filed April 22, 1947, which matured into Patent No. 2,550,098

on April 24, 1951, and may support the concave 28 by means of pins 29, engaged by hooks 30 integral with the concave and extending upwardly through appropriate openings in the holder, as there described.

The upper frame further comprises an upper cylindrical section 31, having lower and upper outwardly projecting flanges 32 and 33, the former being seated upon the arcuate members 25 and secured in place by bolt and nut assemblies 34, extending through the flange 23, the ring 24, the arcuate members 25 and the flange 32.

The upper flange 33 serves as a support for an inwardly projecting, annular cover casting or spring cage 35, held in place by tie bolts 36 having outwardly flaring heads at their lower ends counter-sunk in correspondingly shaped recesses in the arcuate members 25 and having nuts 37 on their upper ends. Although only one such tie bolt is shown in the accompanying drawings, it will be understood that an annular series is employed.

The cover casting 35 has its undersurface shaped to provide a plurality of bosses 38 and annular recesses 39, constituting upper end seats for compression springs 40, engaging upwardly projecting bosses 41 on the concave backing 27, permitting limited upward tilting movement of the concave, under the influence of forces transmitted thereto by non-crushable objects, such as tramp iron, entering the crushing zone, as explained in the above identified application.

A cylindrical casing 45 for confining the material delivered to the crusher may be supported upon the cover plate 35, and the springs 40 may be isolated from the material by a cylindrical guard 46, supported on the concave holder for vertical sliding movement with respect to the cover plate 35.

An upper spider 50, secured at its outer extremity to and carried by the cover casting 35, terminates centrally in a hub 51, having a keyed connection 52 with a bearing sleeve 53, herein-after described, permitting relative vertical movement between the sleeve and the hub.

The inwardly projecting annular member 17 associated with the lower frame section constitutes a support for the lower race of a thrust bearing assembly 60, arranged on a vertical axis and including a plurality of radially arranged roller bearings or the equivalent. The upper race of this assembly carried the outwardly projecting flange 61 of a cylindrical member or eccentric 62. The latter includes an upwardly projecting cylindrical body 63 journalled for rotation in the hub 15 coaxially with liner 60, with a stationary bearing sleeve or bushing 64 interposed between its outer surface and the inner surface of the hub. A ring gear 65, fast on the flange 61 of the cylindrical member or eccentric is disposed in mesh with a driving pinion 66, carried by a drive shaft 67, journalled bearings carried by a lateral extension 68 of the lower housing 14 and receiving rotation from any suitable source of power.

The cylindrical interior of the eccentric body 63 is disposed on an axis eccentric with respect to the axis of bearing 60 and the outer surface of the body, and inclined with respect to the vertical, the axes of the interior and exterior surfaces of the eccentric intersection at the point of no motion 70. The bottom surface 71 of the eccentric interior is normal to the axis thereof and terminates centrally in an aperture 72. The bottom surface constitutes a support for the lower

race of a thrust bearing assembly 73, the upper race of which supports the lower end 74 of a shaft supporting sleeve 75. The latter includes an interior transverse wall 76 and an upwardly extending cylindrical side wall 77, having its inner and outer surfaces concentric to the inner surface of the eccentric and coaxial with the bearing assembly 73. A wear plate 78 may be interposed between the bottom wall 76 of the sleeve 75 and the lower end face of the gyratory shaft 80.

At its upper end, the stationary hub 15 carries an inwardly projecting, annular plate 85, having an upwardly extending, outer marginal rib 86 and a plurality of apertures 87 spaced equally therearound. The plate 85 extends inwardly over the upper end of the eccentric sleeve 63 and makes sliding contact with the upper end face 88 of the shaft supporting sleeve 71. Within the apertures 87 in the plate 85, there are a plurality of downwardly extending pipe sections 89, disposed in spaced relation to the walls of vertical recesses 90 formed in the inner face of the hub 15, each recess being in communication through a vertical groove 91 with an annular groove 92 disposed substantially midway in the vertical height of the inner face of the hub 15. The annular groove 92 communicates with a passage 93 formed in the lower frame section 11, arranged to deliver oil to the lateral extension 68, for lubrication of the bearings for the shaft 67, as herein-after explained.

The undersurface of the eccentric 62 carries a positive displacement pump casing 100, having intermeshing gears 101, 102 therein, the former being fast on a shaft 103 having a laterally projecting arm 104 secured to its lower end, in engagement with a post 105, projecting upwardly from the bottom of the lower housing section 16, to restrain the shaft 103 and gear 101 against rotation with the pump housing 100, thereby to cause the gear 102 to planetate about the stationary gear and to deliver oil under pressure from the oil reservoir, defined by housing sections 14 and 16, to the interior of the eccentric, through the central opening 72 in the bottom thereof. It should be understood that the lower frame or casting 10, including housing sections 14 and 16, define an oil reservoir and that the oil normally stands at the level indicated by the broken line 106. The oil forced upwardly by the gear pump floods the bearing assembly 73, fills the hollow interior of the shaft sleeve 75, below the transverse wall 76, and is forced laterally through passage 107 formed therein. The eccentric side wall is provided with vertically extending flats or grooves 108, 109 in its inner and outer surfaces, constituting conduits for the flow of oil to the upper end of the eccentric, and to lubricate the surface contact between the inner face of the eccentric and the outer surface of the shaft supporting sleeve, and between the outer surface of the eccentric and the inner surface of the bushing 64, fixed to the inner face of the hub 15. Oil flowing upwardly through groove 108 to the upper end face of the eccentric is received in a plurality of grooves 110 formed therein. As shown in Figure 3 these grooves are curved and inclined outwardly and rearwardly with respect to the direction of rotation of the eccentric, with the result that the oil is forced outwardly therein under the influence of centrifugal force, to return between the outer face of the eccentric and the inner face of the sleeve 64, the oil being confined by the upper plate 87.

Some oil escapes inwardly through the sliding fit between the upper end face 88 of the shaft supporting sleeve 77 and the plate 85, and substantially fills the space 111, between the lower end of the shaft 80 and sleeve 77. As the oil overflows to the upper surface of plate 85, it will be confined by the marginal rib 86 and will flow downwardly through the apertures 87 and pipes 98 into passages 90 and 91, to the annular groove 92 and the lateral conduit 93, for delivery to the bearings for shaft 67. The pipes 89 prevent any oil, thrown outwardly by centrifugal force by the eccentric 63, from splashing upwardly through apertures 87 in plate 85.

The eccentric sleeve 63 is provided with an aperture 112, establishing communication between vertical passages 108 and 109. The aperture may be positioned near the upper ends of the vertical grooves or flats as suggested in Figure 1 or adjacent the passage 107, as shown in Figure 2. In any event, there will be a preferential flow of oil upwardly through passage 108 and the space between the shaft supporting sleeve and the eccentric, and downwardly through the space between the eccentric and the bushing 64 and passage 109, as a result of the additional pressure applied to the oil by the centrifugally acting grooves 110 in the upper end face of the eccentric.

In the oil reservoir within the lower casing section 16, there is disposed a coil of tubing 115, having inlet and outlet fittings 116 and 117, for the circulation through the coil of a cooling medium, such as water or the like. Such coils have been used in the past, in an attempt to reduce the temperature of the oil in gyratory crushers, but their efficiency has not been what might be desired.

A pipe 113, disposed within the lateral passage 93, extends through the bushing sleeve 64 and leads to a pressure gauge, to indicate the oil pressure in the system as a whole and more particularly, the pressure conditions between the sleeve and the outer surfaces of the eccentric.

The present invention provides means for positively circulating the oil in the reservoir in heat exchange relation to the coil 115. Supported from the floor of the lower housing section 16 is a fixed baffle means or conduit member, constituting a centrifugal pump stator, and including an axially disposed cylindrical section 118, having a plurality of openings 119 adjacent its lower end and a laterally flaring, outwardly projecting upper portion 120. Above the latter portion, and arranged coaxially with the cylindrical portion 118 are a plurality of laterally projecting vanes 121, curved rearwardly with respect to the direction of rotation of the eccentric and secured at their inner ends to the gear pump casing 100 for rotation therewith. These vanes constitute the impeller or rotor or a centrifugal pump, discharging laterally in the space between the outwardly flaring, laterally directed flange 120 of the stator and the bottom surface of the eccentric. The cylindrical portion 118 of the stator constitutes the inlet, delivering oil axially and upwardly to the impeller, by inflow through the openings 119. Hence, the oil is positively circulated at all times, downwardly and inwardly, over the lower pipes of coil 115, through openings 119, upwardly to the impeller and outwardly past the upper pipes of the coil, forcefully into lubricating relation to the bearing assembly 60.

The shaft 60 carries the usual crushing head 130, upon which a mantel 131 is secured by a

nut 132. The lower end of the head supports a sealing ring 133, making sliding engagement on a spherical surface with a ring 134 embracing the hub 15, thereby effectively preventing the admission of dust to the parts within the hub.

A floating crushing ring 135 may be interposed between the mantel 131 and the concave 28, as is understood in the art.

At its upper end, the shaft is surmounted by 10 an upwardly and inwardly tapering bearing cap 140 disposed within the bearing sleeve 53, and having its upper end in spherical sliding contact with a sealing ring 141, carried by the bearing 53 and interposed between the cap and a nut 142 having a complementary spherical undersurface. A gyratory fed plate 145 may be secured to the upper end face of the shaft, for controlling the delivery of material to the crusher, and may have vertically sliding connection with a weighted 20 sealing ring 146 having a lower spherical surface making sliding contact with a complementary, upwardly facing surface on a sealing plate 147 carried by the central hub 51 of the spider. All of the above mentioned spherical surfaces are 25 struck about the point of no motion 70, as a center.

In operation, the eccentric 62 is rotated by 30 gears 66 and 65, thereby imparting gyratory movement to the lower end of the shaft, supported in the sleeve 75 mounted on the thrust bearing 73, the upper end of the shaft being simply guided by the bearing 53 within the spider hub 51.

The rotation of the eccentric results in the oil 35 circulation previously described. All parts are maintained lubricated and the oil is kept cool.

Vertical adjustment of the crushing space between the mantel and concave may be effected by 40 loosening the locking ring 22 and rotating the entire upper frame, thereby raising the concave. The slideable, key connection between the spider hub and the bearing 53 for the upper end of the shaft permits relative vertical movement of the spider with respect to the shaft, its upper bearings, and the crushing head, but prevents relative rotation between the bearings and the spider.

The invention is not limited to the details of construction shown in the accompanying drawings and described above, but covers all modifications coming within the appended claims and 50 their equivalents.

I claim:

1. A crusher comprising a fixed lower frame, an upper frame secured thereto for relative vertical adjustment with respect thereto, a spider carried by the upper frame having a central opening, an upper shaft bearing in the opening restrained against rotation with respect thereto, an annular thrust bearing supported in the lower frame on a vertical axis, an upright cylindrical member journaled for rotation coaxially on and supported by said thrust bearing, said member having a cylindrical upwardly opening eccentric interior disposed in angular relation to its axis 60 of rotation, and anti-friction thrust bearing in the bottom of and coaxial with the interior of said member, a cylindrical sleeve closely fitting said interior and supported on the bearing therein, a shaft having its lower end disposed within 65 and supported exclusively by said sleeve and projecting upwardly therefrom on said angularly disposed axis, a crushing head carried by said shaft, an upwardly facing mantle thereon, and a downwardly facing, annular concave carried by the upper frame for vertical adjustment therewith,

the upper end of the shaft being disposed within said upper shaft bearing.

2. A crusher comprising a fixed lower frame, an upper frame secured thereto, a spider carried by the upper frame having a central opening, an upper shaft bearing in the opening restrained against rotation with respect thereto, an annular thrust bearing supported in the lower frame on a vertical axis, an upright cylindrical member journalled for rotation coaxially on and supported by said thrust bearing, said member having a cylindrical upwardly opening eccentric interior disposed in angular relation to its axis of rotation, an anti-friction thrust bearing in the bottom of and coaxial with the interior of said member, a cylindrical sleeve closely fitting the interior, supported on the bearing therein and having a transverse wall normal to its axis, a shaft having its lower end supported exclusively by said transverse wall and projecting upwardly therefrom on said angularly disposed axis, a crushing head carried by said shaft, an upwardly facing mantel thereon and a downwardly facing, annular concave carried by the upper frame, the upper end of the shaft being disposed within said upper shaft bearing.

3. A crusher comprising a fixed lower frame, an upper frame secured thereto for vertical adjustment with respect thereto, a spider carried by the upper frame having a central opening, an upper shaft bearing in the opening restrained against rotation with respect thereto but having vertically slidable connection therewith, an annular thrust bearing supported in the lower frame on a vertical axis, an upright cylindrical member journalled for rotation coaxially on and supported by said thrust bearing, said member having a cylindrical upwardly opening eccentric interior disposed in angular relation to its axis of rotation, an anti-friction thrust bearing in the bottom of and coaxial with the interior of said member, a cylindrical sleeve closely fitting the interior, supported on the bearing therein and having a transverse wall normal to its axis, a shaft having its lower end supported exclusively by said transverse wall and projecting upwardly therefrom on said angularly disposed axis, a crushing head carried by said shaft, an upwardly facing mantel thereon and a downwardly facing, annular concave carried by the upper frame, the upper end of the shaft being disposed within said upper shaft bearing.

4. A gyratory crusher comprising a fixed lower frame or casing defining an oil reservoir, an annular thrust bearing supported in said frame on a vertical axis, an upright cylindrical member journalled for rotation coaxially on said bearing, said member having a cylindrical, upwardly opening eccentric interior disposed in angular relation with respect to its axis of rotation, an anti-friction thrust bearing in the bottom of the interior of said member, a shaft having its entire weight supported by the last mentioned bearing and projecting upwardly therefrom on said angularly disposed axis, a lubricant pump carried by said member in said reservoir to deliver oil therefrom to the interior of the member for lubrication of said anti-friction thrust bearing, a plurality of outwardly projecting vanes supported below the eccentric for rotation about the axis thereof and deriving rotation therefrom to act as a centrifugal impeller, an upwardly extending centrifugal stator below said vanes cooperating therewith to circulate the oil in said res-

ervoir, and oil cooling means in the path of circulation of the oil.

5. A crusher comprising a lower frame or casing defining an oil reservoir in its lower portion and including an upwardly projecting cylindrical hub, an annular thrust bearing in said casing on a vertical axis, an upright cylindrical member journalled for rotation in said hub coaxially on said bearing, said member having a cylindrical, upwardly projecting eccentric interior surface having an axis disposed in angular relation to its axis of rotation, an anti-friction thrust bearing in the bottom of and coaxial with the interior surface of said member, a sleeve closely fitting said interior surface and supported by the bearing therein, a shaft having its lower end supported within and exclusively by said sleeve and projecting upwardly on said angularly disposed axis, a positive displacement pump carried by the bottom of said member, delivering oil from the reservoir forcefully to the interior of the member for lubrication of the anti-friction bearing, the sleeve, the eccentric and the hub surfaces and for return to the reservoir, a plurality of outwardly projecting vanes connected to and rotatable with the displacement pump and constituting a centrifugal impeller, fixed baffle means in the reservoir for circulating the oil under the influence of the impeller through a definite path, and oil cooling means in said path of circulation of the oil.

6. In a gyratory crusher, a lower casing or frame defining an oil reservoir, a rotatable eccentric journalled for rotation on a vertical axis in the frame, a plurality of outwardly projecting vanes mounted for rotation in the reservoir on the axis of the eccentric, constituting a centrifugal impeller and deriving rotation from the eccentric, baffle means associated with the impeller, having a downwardly extending, axially disposed cylindrical portion and an outwardly turned upper flange below the vanes, arranged to guide the oil through a definite circulatory path under the influence of force imparted thereto by the impeller, and oil cooling means in the path of circulation of the oil.

7. In a gyratory crusher, a lower casing or frame defining an oil reservoir, an eccentric journalled for rotation on a vertical axis in the frame, a positive displacement pump housing in the reservoir suspended from the bottom of the eccentric and rotatable therewith, a plurality of outwardly projecting vanes suspended from the bottom of the eccentric and rotatable therewith and constituting a centrifugal rotor, an upwardly extending centrifugal stator within said reservoir axially aligned with the rotor, defining an intake for delivering oil to the rotor and having a laterally turned portion defining a circumferential discharge conduit, and cooling coils in the path of circulation of oil discharged by said impeller.

8. In a gyratory crusher, a lower casing or frame defining an oil reservoir, an eccentric journalled for rotation on a vertical axis in the frame, a positive displacement pump housing in the reservoir suspended from the bottom of the eccentric and rotatable therewith, a plurality of outwardly projecting vanes carried by the pump housing and constituting a centrifugal rotor, an upwardly extending centrifugal stator within said reservoir axially aligned with the rotor, defining an intake for delivering oil to the rotor and having a laterally turned portion defining a circumferential discharge conduit, and cooling coils in

the path of circulation of oil discharge by said impeller.

9. A gyratory crusher comprising a lower casting providing an oil reservoir and having an integral, cylindrical, upstanding hub shaped to provide oil return passages, an eccentric journaled for rotation in the hub, a shaft sleeve within the eccentric, a crusher shaft having its lower end disposed within the sleeve to receive gyratory motion from the eccentric, an annular plate secured to the upper end of the hub, having an upstanding outer marginal rib and projecting inwardly in overlapping relation to the upper end of the eccentric and the sleeve, said plate having apertures aligned with the passages in the hub, and means for delivering oil under pressure upwardly adjacent the inner surface of the eccentric for overflow to the upper surface of said plate and for return through said apertures and return passages.

10. A gyratory crusher comprising a lower casting providing an oil reservoir and having an integral, cylindrical, upstanding hub shaped to provide oil return passages, a non-rotatable liner in the hub, an eccentric journaled for rotation in the liner and having a plurality of outwardly and rearwardly extending grooves in its upper end face, a shaft sleeve within the eccentric, a crusher shaft having its lower end disposed within the sleeve to receive gyratory motion from the eccentric, an annular plate secured to the upper end of the hub, having an upstanding outer marginal rib and projecting inwardly in overlapping relation to the upper end of the liner, the eccentric and the sleeve, said plate having apertures aligned with the passages in the hub, and means for delivering oil under pressure upwardly adjacent the inner surface of the eccentric for delivery under the influence of centrifugal force through said end grooves to the outer surface of the eccentric and for overflow to the upper surface of said plate and for return through said apertures and return passages.

11. A gyratory crusher comprising a lower frame or casing providing an oil reservoir and having an integral cylindrical upstanding hub shaped to provide oil return passages, a non-rotatable liner in the hub, an eccentric journaled for rotation in the liner, having a plurality of outwardly and rearwardly curved grooves on its upper end face and a vertically extending groove on its inner vertical face, a shaft sleeve within the eccentric, a gyratory crusher shaft having its lower end disposed within and supported by the sleeve to receive gyratory motion from the eccentric, an annular plate secured to the upper end of the hub, having an upstanding marginal rib, and projected inwardly in overlapping relation to the upper end of the liner, the eccentric and at least a portion of the upper end of the sleeve, said plate having apertures aligned with the passages in the hub, and means for forcing

oil under pressure upwardly through the groove in the inner vertical surface of the eccentric for delivery under the influence of centrifugal force through the grooves in the eccentric end face to the liner and the outer vertical surface of the eccentric and for overflow into the interior of the sleeve and to the upper surface of the plate and for return to the reservoir through said apertures and hub passages.

12. A gyratory crusher comprising a lower frame or casing providing an oil reservoir and having an integral cylindrical upstanding hub shaped to provide oil return passages, a non-rotatable liner in the hub, an eccentric journaled for rotation in the liner, having a plurality of outwardly and rearwardly curved grooves on its upper end face and vertically extending grooves on its inner and outer vertical faces, a shaft sleeve within the eccentric, a gyratory crusher shaft having its lower end disposed within and supported by the sleeve to receive gyratory motion from the eccentric, an annular plate secured to the upper end of the hub, having an upstanding marginal rib, and projected inwardly in overlapping relation to the upper end of the liner, the eccentric and at least a portion of the upper end of the sleeve, said plate having apertures aligned with the passages in the hub, and means for forcing oil under pressure upwardly through the groove in the inner vertical surface of the eccentric for delivery under the influence of centrifugal force through the grooves in the eccentric end face to the liner and the outer vertical surface of the eccentric and for overflow into the interior of the sleeve and to the upper surface of the plate and for return to the reservoir through said apertures and hub passages, said eccentric having a passage through its vertical side wall establishing communication between the vertically extending grooves therein.
